UNITED STATES PATENT OFFICE.

PETER J. SLOAN, OF DENVER, COLORADO, ASSIGNOR, BY DIRECT AND MESNE ASSIGNMENTS, OF ONE-HALF TO SANFRED ERICKSON AND FIFTY PER CENT TO ALBERT J. COLE, BOTH OF DENVER, COLORADO.

ELECTRIC RAILROAD LANTERN.

Application filed April 19, 1920. Serial No. 374,837.

To all whom it may concern:

Be it known that I, PETER J. SLOAN, a citizen of the United States, residing at Denver, in the county of Denver and State 5 of Colorado, have invented new and useful Improvements in Electric Railroad Lanterns, of which the following is a specification.

The present invention is directed to improvements in portable electric lanterns, and 10 more particularly to one designed for use by trainmen.

The invention has for its object to provide a lantern of this nature so constructed that lights of different colors, such as red, green 15 and white can be quickly displayed, or extinguished when desired.

A further object of the invention is to provide a lantern of this character constructed in such a manner that the electric 20 bulbs will be effectively protected against possible injury, the bulbs being so arranged that when illuminated the rays therefrom can be seen from a long distance.

Still another object of the invention is to 25 provide a lantern which is extremely simple in construction, durable, and one which is efficient in operation.

With these and other objects in view, this 30 invention resides in the novel features of construction, formation, combination and arrangement of parts to be hereinafter more fully described, claimed and illustrated in the accompanying drawings, in which:

The figure represents a perspective view 35 of the lantern.

Referring to the drawings, 1 designates a metallic container, preferably circular in cross section, and upon the upper end of which is mounted a top 2, said top being 40 threaded, as at 3, and is adapted to thread upon the upper end of the container, and has its lower end provided with a bottom cap 8. This container of course has located therein the usual batteries, as is customary.

Depending from the bottom cap 8, are 45 sockets 15 and 16 in which are screwed, respectively, the stems of the bulbs 17 and 18, the former being colored green, while the latter is colored red. The socket 16 is properly insulated from the plate 11 so that the bulbs 17 and 18 may be selectively illuminated.

Suitably fixed to the exterior of the container 1 is a switch casing 19, and slidably

associated therewith are buttons 20. These 55 buttons are employed for controlling the current to the bulbs, as is usual.

The lantern as a whole is supported on a skeleton frame 25, which consists of legs 26, preferably four in number, the upper ends 60 of which are suitably fixed to the flange 7 of the bottom cap 8, while the lower ends thereof are secured to a horizontal base ring 27.

Having their outer ends fixed to the legs 65 26 at points somewhat above the ring 27 are cross bars 28, said bars being formed centrally with depressions 29 which intersect at right angles, and form a seat 30. Suitably fixed in this seat is the tubular base 70 of the socket 31, and being mounted in this manner it is obvious that the same will be rigidly supported. Engaged in the socket 31 is a white bulb 32, the same receiving current through a wire 25', which leads from 75 the container. To protect this wire a tube 33 is employed and has its upper end located in the container 1, and passes through the bottom cap 8, and from thence longitudinally of the adjacent leg 26. The tube 80 then follows the adjacent bar 28 to the socket 31, and since the wire 25' is passed through the tube the same is protected against possible injury.

It will be noted that the bulbs 17 and 18 85 are positioned near the side line of the container 1, whereby the rays therefrom can be seen from a great distance when the lantern is being carried or is at rest on the ground.

The bulb 32, which is white, is disposed 90 below the bulbs 17 and 18, and in triangular relation thereto. By arranging the bulbs in this manner it is obvious that the presence of one will in no way interfere with the other, therefore the rays may be seen 95 without obstruction.

A bail 35 is provided, and may be rigidly or hinged connected to the container, as desired.

Since the skeleton frame is rigid with the 100 bottom cap 8 it will be apparent that former may be grasped in one hand and the latter in the other, whereupon the bottom cap can be easily unscrewed from the container, and since the top 2 can be readily removed it 105 is obvious that a lantern has been provided which can be easily and quickly assembled or disassembled.

From the foregoing description taken in connection with the accompanying drawings, the advantages and operation of the lantern will be apparent to those skilled in the art.

What is claimed is:

1. A lantern of the class described, comprising a container, supporting legs depending from the container, horizontal cross bars connecting the legs and having their central portions formed with depressions arranged in intersecting relation to provide a seat, and a socket rigidly mounted in the seat.
- 15 2. A lantern of the class described, comprising a container, legs depending from the container, a base ring fixed to the lower ends of the legs, horizontal bars connecting the legs above the ring and having central intersecting depressed portions providing a seat, a socket rigidly mounted in the seat, a pair of sockets carried by the bottom of the container and disposed in triangular re-

lation with the first named socket, and bulbs in the sockets.

3. A lantern of the class described, comprising a container, a top threaded on the container, a removable bottom cap threaded on the container, a skeleton frame removable with the cap and comprising legs having their upper ends fixed to the cap, a horizontally disposed base ring fixed to the lower ends of the legs, cross bars connecting the legs and having their central portions formed with depressions and arranged in intersecting relation, a bulb supported at the intersection of the cross bars, and a pair of bulbs associated with the bottom cap.

In testimony whereof I have hereunto set my hand in presence of two subscribing witnesses.

PETER J. SLOAN.
